UNITED STATES PATENT OFFICE.

HENRY KNICKMANN, OF EAST NEW YORK, N. Y.

JEWELER'S CABINET.

SPECIFICATION forming part of Letters Patent No. 331,719, dated December 1, 1885.

Application filed June 11, 1885. Serial No. 168,377. (No model.)

To all whom it may concern:

Be it known that I, HENRY KNICKMANN, a citizen of the United States, residing at East New York, in the county of Kings and State 5 of New York, have invented new and useful Improvements in Jewelers' Cabinets, of which the following is a specification.

My invention consists in a cabinet for pin-tongues and the like for jewelers' use, composed of a block having a series of concentric cells of varying depths arranged in tiers and extending vertically into the block, and also in such a cabinet consisting of a block having a series of concentric holes arranged in tiers, 15 which extend completely through the block, and plugs of cork or similar material for closing the lower ends of the holes to form cells of varying depths. A suitable cover is fitted over the top of the block, all of which 20 is more fully pointed out in the following specification and claims and illustrated in the accompanying drawings, in which—

Figure 1 represents a vertical section of my improved case for pin-tongues and the like. 25 Fig. 2 is an elevation of the same with the cover removed. Fig. 3 is a plan view of Fig. 2.

Similar letters indicate corresponding parts.

In the drawings, the letter A designates a 30 cylindrical block, the bottom of which is flat, while its upper surface is modeled in tiers a b c, which decrease from the lower one upward sufficiently in diameter to leave an annular surface for the vertical holes, which 35 form cells B for the reception of the articles, and which are circumferentially arranged on the said tiers, and are also arranged with varying depths for different sizes of the pin-tongues. In the example shown in the drawings, all these holes B extend completely 40 through the block from top to bottom, and are plugged at suitable distances from the bottom of the block A, so as to leave corresponding depths from the top of the block for the reception of the pin-tongues, and by the use of the said plugs D the various depths are 45 easily fixed. Instead of drilling the holes which form the cells completely through the block, they may extend a little farther than 50 is requisite with the length of the pin-tongues,

which they are intended to receive, and a plug of cork or other similar material may be forced to the bottom of the same for the purpose of protecting the points of the pin-tongues or other articles which may be placed into the 55 holes. The edge of the block surrounding the bottom of the lowest tier is provided with a groove, d, for the reception of the lower edge of a cover, E, Fig. 1, of glass or similar material, the latter fitting snugly into the 60 groove in order to prevent dust from entering the cabinet. The cells in each tier are ranged from a minimum depth to a maximum depth, in order that each tier may contain a complete set of pin-tongues, each cell being marked, as 65 shown in Fig. 2, with a number indicating the size of the pin-tongues. The central hole, D', as shown in the drawings, is also filled with pin-tongues; but I usually prefer to make this cell of a slight depth, so as to adapt it 70 for the reception of small parts of the pin-tongues, and I provide the same with a plug or stopper to prevent the accidental loss of these parts. If desired, the points of the pin-tongues can be forced into the cork at the bottom of the cells, whereby the same are prevented from falling out in case the cabinet be 75 upset.

The convenience of such a cabinet for jewelers' use is apparent without further demonstration, as it forms not only a very neat receptacle for the said pin-tongue, but the exact size desired can be selected without the slightest trouble. It is evident that my cabinet can also be used as a receptacle for needles or the 85 like.

What I claim as new, and desire to secure by Letters Patent, is—

1. A cabinet for pin-tongues and the like, consisting of a block having a series of concentric cells of varying depths arranged in tiers and extending vertically into the block, substantially as shown and described. 90

2. A cabinet for pin-tongues and the like, consisting of a block having a series of concentric cells of varying depths arranged in tiers and extending vertically into the block, cork or similar material placed in the bottom of the cells, and a cover fitting over the block, substantially as shown and described. 95 100

3. A cabinet for pin-tongues and the like, consisting of a block having a series of concentric holes arranged in tiers and extending completely through the block, plugs inserted 5 in the bottom of the same to form cells of varying depths, and a cover fitting the block, substantially as shown and described.

In testimony whereof I have hereunto set my hand and seal in the presence of two subscribing witnesses.

HENRY KNICKMANN. [L. s.]
